UNITED STATES PATENT OFFICE.

GRACE F. McCARTY, OF CHICAGO, ILLINOIS.

TOILET-POWDER PACKAGE.

Application filed January 20, 1921. Serial No. 438,579.

To all whom it may concern:

Be it known that I, GRACE F. McCARTY, a citizen of the United States, residing at Chicago, in the county of Cook and State of Illinois, have invented certain new and useful Improvements in Toilet-Powder Packages, of which the following is a specification.

One part of the present invention relates to a package containing toilet powder, together with means for applying the powder to the face, and has for its object to provide a cheap and convenient but effective envelope or container for the powder and an appliance both for merchandising and for protection during use, and which will at the same time keep the appliance in contact with the powder so that it will be charged with a supply of the same when removed from the envelope. To this end one feature of the invention consists in providing an envelope of paper or other suitable material of tapering form, together with an appliance having a correspondingly formed tapered portion so that a limited quantity of powder will be caused to accumulate around the reduced portion of the appliance which will ordinarily be used as the portion for contact with the face in applying the powder. Preferably the envelope is made with a secondary pocket carried by its flap into which the primary pocket containing the powder and appliance can be folded for further security and efficiency in packaging.

A second part of the invention relates to an appliance for applying powder to the face, and has for its object to provide a device of this kind which will afford a plurality of surfaces adapted to be successively exposed in position for use. To this end, this part of the invention consists in folding a cloth or fabric of suitable size upon a plurality of diameters so that it will develop a folded body of a plurality of plies of the material with limited portions of the surface of the fabric exposed for use, namely, on opposite sides of the section resulting from the folding; the shape of the folded fabric which produces the appliance being angular, or provided with a corner which affords a tapered outline to the applying surface to render it more convenient and effective in use. The plies or folds of the appliance are penetrated transversely by a cord which is adapted to hold them together and which is of such length as to permit the

folds to be separated for reversing the lines of folding for bringing new portions of the surface into position for use as exposed portions thereof become soiled.

In the accompanying drawing—

Figure 1 is a view of the complete package, including the transparent envelope and the contained powder and appliance.

Figure 2 is an inner face view of the envelope with its pockets or flaps distended.

Figure 3 is a perspective view of the appliance folded for use.

Figure 4 is a perspective view of the same partially unfolded and in the course of reversal on one of its lines of folding to expose two new surfaces; and

Figure 5 is a perspective view of the device of Figures 3 and 4 opened on its two intersecting lines of folding and in the course of complete reversal.

1 represents the envelope which may conveniently be formed as a rectangle with pockets 2 and 3 hinged together through the medium of the intermediate flexible portion 4 which assumes a diagonal of the rectangle and leaves each pocket with a substantially triangular form or tapered toward its bottom 5. With the envelope constructed in this way, flap with its pocket may be folded into the other pocket to confine the contents and keep the appliance in the tapered portion of the pocket and, therefore, in contact with the contained powder.

6 represents the appliance which is in the form of a sheet of cloth or fabric of substantially circular, approximately rectangular, or other suitable form, as suggested in Figure 5, adapted to be folded upon a plurality of diameters, for instance, its two diameters 6^a and 6^b to bring it into the form shown in Figure 3, in which it will have the tapered portion or corner 7 of advantageous form for applying the powder to the face. Appliance 6 is provided with a securing cord 8 inserted transversely through its several plies or folds, as shown in Figure 3, and which therefore holds the plies or folds together until it becomes desirable to reverse the folding. When the two outer surfaces of the appliance 6 become soiled, it will be opened out on its half diameter 6^b, as suggested in Figure 4, until the inner loop 8^a of the cord 8 can be grasped, and then the cord will be drawn and the folds turned back to expose two new surfaces. When all four of the folded surfaces afford

ed by the folding suggested in Figures 3 and 4 have been used, the device can be opened as suggested in Figure 5 and completely reversed, first upon the diameter 6^a and then 5 upon the diameter 6^b in order to afford four additional folded surfaces. In this way it will be seen that the device affords eight working surfaces and always retains its shape, with the tapered portion serving the 10 combined function of insuring contact with the powder contained in the tapered portion of the envelope and facilitating contact with portions of the face to be reached with the powder.

15 An important feature of the preferred embodiment of the appliance consists in developing the plies or folds into substantially angular form, for instance, a triangle, with the confining cord 8 passing transversely 20 through the same near the free edges of the plies and intermediate of two of the corners of the fold and leaving the corner 7, with which to apply the powder, built up of the folded portions of the goods.

25 Obviously, the form of the device is such that a substantial body of powder can be placed on the interior of the folds and caused to work its way through the pores of the fabric; or the appliance may be used by 30 bringing its outer surface into contact with the supply of powder.

I claim:

1. A powder appliance comprising a piece of fabric folded upon a plurality of diameters to develop superposed plies of material of substantially angular form, having a cord passed transversely through said plies adjacent the free edges thereof and intermediate of two corners of the plies, 35 40 and leaving a third corner developed from folds of the material for use in applying powder.

2. In combination with an envelope constructed with a tapering pocket, an appliance 45 consisting of a piece of fabric folded

upon a plurality of folded diameters and developing a body of substantially angular plies or folds having a cord passing through the plies adjacent the free edges thereof and leaving a corner developed from folds of 50 the piece and adapted to conform to the tapered portion of the envelope.

3. A powder appliance comprising a body of fabric folded into a plurality of substantially triangular plies, and a correspondingly formed triangular envelope opening along one of its sides, adapted to receive the appliance with its apex foremost and to contain powder in its apex opposite its open side and hold said powder in contact with 55 the apex of the appliance.

4. In a powder appliance comprising a body of fabric folded into a plurality of substantially triangular plies, a controlling string penetrating the plies of said fabric 65 adjacent to a side of the triangle thereof, and a correspondingly formed triangular envelope opening along one of its sides adapted to receive the appliance with its apex foremost that lies opposite the string, 70 and adapted to contain powder in the apex opposite its open side and hold said powder in contact with the apex of the introduced appliance.

5. A powder appliance comprising a body 75 of fabric folded into a plurality of substantially triangular plies, and a correspondingly formed triangular envelope opening along one of its sides, adapted to receive the appliance with its apex foremost and to contain powder in its apex opposite its open side 80 and hold said powder in contact with the apex of the appliance; said envelope having a triangular flap connected through one of its sides to the open side of the envelope, and 85 constructed with a pocket adapted to receive the envelope within it.

Signed at Chicago, Illinois, this 15th day of January, 1921.

GRACE F. McCARTY.
